(71) Applicant: **Sears Brands, L.L.C.**, Hoffman Estates, IL (US)

(Continued)

(72) Inventor: **Nora Sun**, New York, NY (US)

Primary Examiner — Kevin Rudzinski

(73) Assignee: **Sears Brands, L.L.C.**, Hoffman Estates, IL (US)

(74) *Attorney, Agent, or Firm* — McAndrews Held & Malloy, Ltd.

(**) Term: **15 Years**

CLAIM

(21) Appl. No.: **29/537,083**

The ornamental design for a display screen or portion thereof with an icon, as shown and described.

(22) Filed: **Aug. 21, 2015**

DESCRIPTION

Related U.S. Application Data

(63) Continuation of application No. 29/464,066, filed on Aug. 12, 2013, now abandoned.

The file of this patent contains at least one drawing/photograph executed in color. Copies of this patent with color drawings(s)/photograph(s) will be provided by the Office upon request and payment of the necessary fee.

(51) **LOC (10) Cl.** **14-04**

FIG. 1 is a front view of a first embodiment of a display screen or portion thereof with an icon showing my new design;

(52) **U.S. Cl.**

FIG. 2 is a front view of another embodiment of a display screen or portion thereof with an icon showing my new design;

USPC **D14/490**

FIG. 3 is a front view of another embodiment of a display screen or portion thereof with an icon showing my new design;

(58) **Field of Classification Search**

FIG. 4 is a front view of another embodiment of a display screen or portion thereof with an icon showing my new design;

USPC D14/485-495

FIG. 5 is a front view of another embodiment of a display screen or portion thereof with an icon showing my new design; and,

CPC G06F 3/048; G06F 3/0482

FIG. 6 is a front view of another embodiment of a display screen or portion thereof with an icon showing my new design.

See application file for complete search history.

(56) **References Cited**

The broken line drawings of the display screen are for environmental purposes only and form no part of the claimed design.
